(57) **CLAIM**

The ornamental design for a gun safe, as shown and described.

DESCRIPTION

FIG. 1 is a right side, front perspective view of a gun safe showing my new design.

FIG. 2 is a front elevational view of the gun safe illustrated in FIG. 1.

FIG. 3 is a back elevational view of the gun safe illustrated in FIG. 1.

FIG. 4 is a left side elevational view of the gun safe illustrated in FIG. 1.

FIG. 5 is a right side elevational view of the gun safe illustrated in FIG. 1.

FIG. 6 is a top view of the gun safe illustrated in FIG. 1.

FIG. 7 is a bottom view of the gun safe illustrated in FIG. 1.

FIG. 8 is a right side, front perspective view of the gun safe illustrated in FIG. 1, shown in an open position.

FIG. 9 is a top view of the gun safe illustrated in FIG. 1, shown in an open position; and,

FIG. 10 is a right side view of the gun safe illustrated in FIG. 1, shown in an open position.

The portions shown in broken lines form no part of the claimed design.

1 Claim, 9 Drawing Sheets
